ELECTROLYTIC SHEET TREATING APPARATUS

Horace J. Paynter, Union, N. J., assignor to American Can Company, New York, N. Y., a corporation of New Jersey

Application February 17, 1940, Serial No. 319,528

11 Claims. (Cl. 204—199)

The present invention relates to an apparatus for treating sheet material and has particular reference to an apparatus for electrolytically treating the sheet primarily by oxidizing a surface in an anodizing step and provision is also made at times for a precleaning treatment in the same apparatus which may take the form of cathodizing cleaning, or may be a combination of anodizing and cathodizing cleaning.

Sheet material, as for example, tin plate, when used in the manufacture of the ordinary tin can, quite frequently has been found to vary in its surface conditions so that when made up into cans, difficulties are often experienced in chemical reaction between the can wall and the contents of the can. One such difficulty appears in the canning of products containing sulphur, the chemical reaction resulting in the formation of dark metal sulphides on the interior can walls which appear as stained and dark colored areas. In other cases rust appears on the inner can wall and often, even when the can walls have been coated or lined with lacquer or other protective coating, such lining over a period of time undergoes decomposition as a result of the chemical reaction between the metal can wall and the product.

Sheets heretofore have been anodically treated as an incident to being made into cans and while a proper anodic treatment does prevent the chemical reactions recited above, or at least does greatly reduce such reaction, considerable difficulty has been experienced with the step of soldering together the treated surfaces. In fact it has been found almost impossible to properly solder an anodized blank without a further treatment of the solder areas. This has been a serious drawback to the anodizing of sheet material for the manufacture of cans.

This difficulty has been overcome in the apparatus of the present invention by shielding all of the solder areas of the sheet, while it is undergoing treatment, in a simple and rapid manner and as a continuous operation. In the same machine the sheet can also be cleaned prior to its anodic treatment and the surface of the sheet which is undergoing oxidization or cleaning is presented to the direct action of the electrolyte while other parts of the sheet are fully protected.

An object of the present invention is the provision of a sheet treating machine having a sheet holder on which the sheet is clamped and held for the treatment in such a manner as to present the surface to be treated directly to the action of an electrolyte which is caused constantly to circu-

late during treatment and thus provide the medium through which flows an electrical treating current whose circuit includes the sheet.

Another object of the invention is the provision of a sheet treating apparatus wherein the sheet is clamped upon a holder with certain areas matted or blocked off in a manner to present the unblocked areas to the action of an electrolyte while the sheet is connected in an electrical treating circuit, the current which flows through the circuit utilizing the electrolyte as a treating medium.

A further object is the provision of a sheet treating apparatus for continuously receiving successive sheets as they are fed into the machine and for holding each sheet with certain surfaces protected, while circulating an electrolyte in contact with exposed or unprotected surface areas, each sheet after treatment being discharged without interruption of a steady flow of the sheets.

Another object of the invention is the provision of an apparatus of the character described which has a sheet holder and clamping means for tightly holding the sheet so that one surface forms the side of an enclosed space or pocket and a part of the holder forms the other side, the sheet constituting one pole in an electrical treating circuit in which the holder constitutes the opposite pole, the space or pocket being filled with an electrolyte which completes the treating circuit, control of the flow of the treating current anodically oxidizing the sheet's surface which is exposed to the electrolyte, or cleaning such surface by cathodic action.

Yet another object is the provision of a rotatable wheel holder in a treating apparatus of this nature, on the periphery of which sheets undergoing treatment are held tightly clamped by a belt passed over the wheel, each sheet so held being directly associated with an individual treating pocket or chamber formed on the wheel by means of which each sheet is electrically treated by the treating medium confined in its pocket.

Still a further object is the provision of such a treating apparatus for sheets having a wheel structure for holding the sheet during treatment which exposes a surface of the sheet to an anodic or to a cathodic action, the sheet constituting one pole of the circuit and the holder constituting the other pole, the sheet being spaced from the active surface of the holder so that the flow of electrical current for such treatment passes through an electrolyte which occupies the space between the pole pieces, the gas which is evolved in the re-

sulting electrolysis being drawn off as it forms so that a more uniform surface treatment is obtained.

Another object is the provision of an apparatus of the character described having a revolving wheel holder to which sheets are fed continuously, the sheets being automatically clamped onto the periphery of the wheel by a belt which passes into engagement with the wheel at such time, the clamping of the sheet onto the wheel closing over and forming an electrolyte pocket or chamber into which the electrolyte is then introduced and caused to circulate so that the surface of the sheet which is presented to the pocket interior is contacted by the electrolyte uniformly on its exposed area, the sheet forming one side of the electrical treating circuit while a wheel part forms the other side but sheet and wheel are insulated against current conduction except through the electrolyte, the direction of flow of the current determining whether there is anodic or cathodic treatment, the apparatus also having devices for controlling the flow of the electrolyte and the direction and timing of the treating current, the electrolyte being drawn off from the pocket upon completion of the treatment and prior to the belt leaving the surface of the wheel as the treated sheet is removed.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a sheet treating apparatus embodying the present invention;

Fig. 2 is a transverse section drawn to an enlarged scale and partly broken away of the wheel holder of the apparatus of Fig. 1 being a view taken substantially along the section line 2-2 of such figure;

Fig. 3 is a sectional detail of certain of the wheel holder parts as viewed along the section line 3-3 in Fig. 2 and on a slightly enlarged scale;

Fig. 4 is a plan view of the parts shown in Fig. 3 as viewed from the outer or convex side of the holder, certain of these parts being broken away to better disclose other constructions therebeneath;

Figs. 5 and 6 are enlarged sectional details taken substantially along the respective section lines 5-5 and 6-6 in Fig. 4;

Fig. 7 is a sectional fragment taken along the line 7-7 in Fig. 2;

Fig. 8 is an end elevation of the wheel holder parts of the apparatus showing certain wiring connections, the point of view being indicated in Fig. 2 by the broken line 8-8, this latter figure being drawn to a greater scale than is Fig. 2;

Fig. 9 is a fragment elevation of such wiring connections, the curved and broken line 9-9 in Fig. 8 suggesting how Fig. 9 is to be viewed;

Fig. 10 is an enlarged transverse section of the central part of the wheel holder of Fig. 2, said view being taken substantially along the section line 10-10 in Fig. 2;

Fig. 11 is an end elevation of the apparatus 70 as it would appear when viewed from a plane having the trace lines 11-11 as indicated in Fig. 1; and

Fig. 12 is a face view of a fragment of a sheet showing by stippling a surface treatment such 75

as could be effected in the apparatus of the present invention.

Referring first to Fig. 1, sheets *a* such as tin plate which are to be treated in the apparatus, 5 are placed in any suitable manner on a continuously moving feeding chain device broadly designated by the letter A. This feeding device advances the sheet toward a rotating wheel holder B on which the sheet is carried through a circular path during treatment.

The wheel holder B is shown in the drawings as of dual construction and constitutes two wheels. On the periphery of each wheel there is provided a series of frame elements D arranged 15 one adjacent the other and each element is so shaped as to accommodate a single sheet *a*. Such a frame provides a support for the individual sheet and holds it substantially uniformly curved on the periphery of the wheel holder B.

20 An endless belt E, which is wider than the sheets being treated, passes over each of the wheel holders, there being two such belts for the apparatus shown in the drawings. Each belt E lies down against the sheets on the frames 25 and thus acts as a clamping device for holding the sheets on the wheels. Each belt is in contact with its associated wheel for substantially 335° and then passes back over suitable pulleys and then around to position where it again 30 engages the wheel holder.

The intervening section where the belt is not on the wheel holders is located adjacent the discharge end of the feeding device A and this permits the placing of each sheet onto its holder 35 as it leaves the feeding device. Upon coming into proper position relative to its frame D the sheet is engaged by the belt E and is then carried around by the rotating wheel holder B. It is during such travel that it is subjected to the 40 desired operations of treatment.

A sheet carried by its holder B, after undergoing the various steps of treatment, thus approaches the position where the clamping belt E passes back and away from the wheel holder. 45 At the time it is released by the belt it comes into the influence of a sheet discharge device F (Fig. 1). This discharge device thereupon operates to remove the treated sheet *a* from the wheel holder and to discharge it from the apparatus.

As best illustrated in Figs. 3, 4, 5 and 6 each frame element D of the wheel holder B constitutes the inner side of a treating chamber or pocket G when a sheet *a* is being held in place on the frame by the belt E. The sheet forms the outer 55 wall of the pocket at such a time, the inner surface of the sheet being spaced a slight distance away from the outer frame wall.

The treating chamber G so formed provides an arcuate space through which an electrolyte 60 may be circulated to effect the treatment desired. Suitable parts of a circulating system, broadly referred to by the letter H, are employed and these parts may include pipes, pump, etc., as best shown in Fig. 1. These will be further described and in some detail as the description 65 proceeds.

The feeding device A for each of the wheel holders preferably comprises one or more endless chains 21 (Fig. 1) which take over suitable sprockets 22 mounted on a horizontal shaft 23 journaled in two or more brackets 24 carried on uprights 25 of a main support frame. Such a frame also includes horizontal beams 26 and tie frame parts 27, foot or pier sections 28 at the base of each upright frame resting on the floor

for support. The feed chains 21 also operate over sprockets 31 carried on a horizontal shaft 32. Shaft 32 may be rotated in a suitable manner and thus constitute a drive shaft for the feeding device A.

A sub-frame 33 may be provided for supporting the drive shaft and other shafts. For example, feeding rollers 34 may be mounted on a horizontal shaft 35, carried in the sub-frame for properly directing the sheets as released by the feeding device A so that they will be correctly located in the frame elements D of the wheel holders B.

The wheel holder B, as previously mentioned, includes a double wheel construction. As best shown in Fig. 2, the two independent wheels are each rotated but in unison on an end of a stationary central sleeve 41 which is carried at its center in a bracket frame generally indicated by the numeral 42. This bracket frame includes a central tubular part 43 which is carried on a main base 44 which may rest upon the floor.

Each rotating wheel holder B is mounted on its end of the sleeve 41 where the latter projects beyond its bracket support 43. Each holder consists of a cylindrical drum 51 (Figs. 2 and 10) which at its center is formed with a bearing hub 52 the inner bore of which carries a bushing 53. Such a bushing turns directly on the supporting sleeve 41.

The outer peripheral wall, marked 54, of the drum 51 carries the wheel proper which is formed with an inner hub 55 and an outer rim 56 (Figs. 2 and 3). Rim and hub are connected all as an integral unit by a pair of parallel disc walls 57, which are tied together by radially disposed intermediate plates 58. Angular webs 59, which are prolongations of the plates 58, extend out from the outer disc wall 57 and merge into the rim 56 thus permitting considerable overhang for the rim wall. This provides for a width of wheel at its periphery or rim that is in excess of any width of sheet to be run through the apparatus.

The peripheral surface of the rim wall 56 of each wheel holder B is depressed at regular intervals to provide for the adjacent frame elements D. This is best shown in Figs. 3 and 4. The edge of one frame element comes very close to the adjacent edge of the adjoining frame element and this construction leaves the inner and outer edges of the rim wall and the connecting transverse sections between the adjacent frame elements as a flush cylindrical surface 60 (see also Fig. 5) against which the belt E presses during its engagement with the wheel holder. This flush surface keeps the belt into a true cylindrical form where it passes over the wheel and insures a better holding action for the sheets a during treatment.

Examining more in detail the individual frame element D, it will be observed by reference to Figs. 4 and 5 that the entire frame is set in a substantially square countersink cut into the outer or peripheral surface 56 of the wheel. The particular shape will, of course depend on the shape of the sheet being treated. An insulating member 61 is disposed to cover the entire bottom of each countersink. Such an insulating member may be a sheet of rubber, cork or the like and is used to cover over and to electrically insulate the frame element D from the wheel holder metallic frame at that place.

A sheet of copper or other good electrical conductor 62 is mounted on top of the rubber sheet 61. It has been found satisfactory to vulcanize

these parts 61, 62 together. The purpose of this will be fully described later.

The particular layout of can body blanks, for example, to be obtained from a sheet a to be treated, will determine what part of the surface area is to be blocked off or protected against treatment. In the drawings, there is shown a matting of all of the edges of the sheet and also a median section which is likewise covered. For this purpose matting strips 63 (Figs. 4 and 5) are used. Such strips are preferably of rubber.

Strips 63 rest directly on the copper sheet 62 and are of a size normally to extend up substantially flush with the surface 60 of the wheel. It is on these strips 63 that a sheet a is clamped by the belt E after coming into proper position on the wheel. When so clamped the matting strips yield sufficiently to permit the upper surface of the sheet, which is engaged by the belt to come down flush with the wheel surface 60, as best shown in Figs. 5 and 6.

In coming into this position the sheet a comes into close surface contact with a copper contact plate 65 (Figs. 4 and 6) which extends over one 25 of the side matting strips 63. This contact plate 65 is connected directly to a wire 66 which extends down through the wheel rim 56, being properly insulated therefrom. Thence it passes through a conduit pipe 67 which is radially disposed on the wheel and which is secured to the inner disc wall 57. This conduit pipe adjacent the center of the wheel is bent at right angles (Fig. 2) and passes outwardly through the drum 51 to a place where the wire 66 is connected to an electrical brush 68 carried in a ring 69 fixed to the drum 51.

Each copper sheet 62 contacts directly with a copper contact plate 71 (Figs. 4 and 5) which extends under one of the side matting strips 63 preferably not far from the contact plate 65. Plate 71 is connected directly to a wire 72 which also extends down through the wheel rim and through the same conduit pipe 67 alongside of the wire 66. The inner end of the wire 72 (Fig. 2) is connected to an electrical brush 73 also carried in the ring 69. The wires 66, 72 are kept at different polarity and are included in the treating circuit which will be fully described hereinafter.

Referring again to the countersunk construction of each individual frame element D (Figs. 2, 3 and 4), it will be observed that for a relatively narrow width at the center of the countersink and extending along its peripheral dimension, that a further countersunk pocket 75 is formed in the rim part 56 of the wheel. A grid section 76 is provided as a support for the rubber insulating sheet 61 in this central section, the grid being formed as an integral part of the wheel and having an oblong space or chamber 77 therebeneath.

Arcuate slots 78 are cut through both rubber and copper sheets 61, 62 (Figs. 3 and 4) so that the pocket 77 is in constant communication with the treating chamber G which it will be recalled is contained in the frame element D between the copper sheet 62 on the inside and the tinplate sheet which is held by the belt E on the outside.

The arcuate slots 78 are cut through the copper sheet 62 and the rubber sheet 61 at a position near the base of the matting strips 63. Obviously 70 different sheets 61, 62 must be used for different patterns of the protected areas of the sheet as determined by the matting strips 63. In other words the slots 78 will be in different positions for different patterns. The grid section 76 allows 75 for this different location of slots 78, which will

always come over some of the holes in the grid and thus give free communication between the space 11 and the treating chamber G. At the same time the rubber sheet 61 will be fully supported in its central region.

The pocket space 11 connects with the outer open end of a radially disposed pipe 79 (Figs. 2 and 3) which is threaded in the rim part 56. The inner end of each pipe 79 (Figs. 2 and 10) is threaded into a collar 81 which is set in an annular boss 82 formed on the outside of the outer disc wall of the drum 51. This collar forms the outer rotatable part of a valve unit which is provided so that treating liquid may be introduced into certain of the pipes 79 and may be cut off from certain other pipes. For this purpose, therefore, the inside of the collar 81 is beveled or inclined at 83 in a more effective rotatable liquid-tight joint for the valve parts.

An inner stationary cylindrical block 85 constitutes the other part of the valve. This block on its inner face is also formed with an inclined or beveled surface 86 on which the valve surface 83 slides in a close fit as the wheel B rotates.

These surfaces are held together under spring tension, the block 85 being bored at 87 (see also Fig. 8) on its outer face to accommodate expansion coil springs 88. An L-sectioned collar 89 (Fig. 2) is mounted on a shouldered end of the stationary sleeve 41 and is securely held in place by a locknut 91 threaded on the end of the sleeve. This collar acts as a thrust bearing for the hub 52 of the rotating wheel B.

A feather 92 carried in the collar 89 cooperates with a featherway 93 cut in the block 85. This construction allows for sufficient floating action between the valve members to make the pressure of the springs 88 effective. At the same time the valve block 85 is held against rotation, the beveled surfaces 83, 86 thus turning relative to each other and maintaining the desired valve action.

As best illustrated in Figs. 2 and 10, an annular groove 95 is cut in the incline face 86 of the block 85. This groove extends through approximately 315 degrees. It is located in the incline face 86 (see also Fig. 10) in such position as to be aligned, at some time during the revolution of the wheel B, with a bore 96 cut in the inclined face 83 of the collar 81 which is at the end of each pipe 79. Therefore, all of the bores 96 which are in communication with the supply groove 95 at any particular time, provide connecting passageways between the supply groove and the treating chamber G at the end of the associated pipe 79.

Obviously where the groove 95 does not extend across the end of a pipe 79, that is where the groove does not align with the associated bore 96, the corresponding chamber G is blocked off as to that particular part of the valve unit. In this manner a liquid electrolyte is supplied to twelve chambers G, for example, while two chambers may be blocked off. This is the reason why the groove 95 extends through about 315 degrees.

The groove 95 is in constant communication with a passageway 97 (Figs. 2 and 10) which extends inwardly from the outer face of the block 85. The outer end of passageway 97 connects with the interior of a flexible hose 98 which is held at one end by a suitable nipple threaded into the end of the passageway and connects at the other end with a pipe 99 which extends longitudinally and in the center of the stationary sleeve 41. This pipe supplies both wheels B, the valve

parts just described being duplicated at the two ends of the sleeve.

A supply pipe 101 (Figs. 1 and 2) is joined into the pipe 99 at its center and extends out through 5 suitable openings at the top which are cut through the sleeve 41 and through the tubular bracket part 43. These pipes 99, 101 are part of the circulating system H and as is best shown in Fig. 1 connect into the discharge side of a liquid pump 102. The intake side of the pump is connected by a pipe 103 to a T-pipe section 104 (see also Figs. 2 and 11). Into this fitting two pipes 105 are connected, one for each side of the machine. The outer end of each pipe 105 is bent down as at 15 106 where it enters into a drainage pan or sump 107 which is located under each wheel B.

The pump 102 forces the treating liquid through the pipe 101 where it divides and passes to the right and to the left, through the pipes 99 and 20 chambers G by way of the pipes 79. Here the anodic or cathodic action takes place on the exposed sheet surface depending upon whether sheet a is positive or negative. The copper sheet 62 is always of opposite polarity. Such polarity is 25 changed automatically as the wheel holders B rotate and this will be further discussed later.

The treating liquid enters the chamber 11 from the pipe 79 and passes up through the grid section 16, thence out through the slots 18 (Figs. 3 and 4) into the treating chamber G. As the liquid, which constitutes the electrolyte, strikes the surface of the sheet a being treated, gas is 30 liberated in the form of bubbles and it is desirable not only that the gas bubbles be withdrawn from the sheet surface as rapidly as possible, but that the electrolyte be circulated constantly thus 35 insuring more uniformity in the treatment. This circulation of the electrolyte is an easy matter by reason of the pump 102 and the other means embodied in the circulating system H now being 40 considered.

Each frame element D is constructed so that a drainage trough 111 surrounds the boundary matting strips 63 (Figs. 3, 4 and 5). The matting strips block off any direct communication between the chambers G and their surrounding troughs but a number of holes 112 are cut through the side strips 63. The electrolyte as it continues to 50 be pumped into the chamber G, constantly escapes into the surrounding trough 111 by way of the holes 112.

It will be observed (Fig. 4) that the holes 112, which extend through the side marginal matting strips 63, are located close to the transverse strips. In the pattern shown in this figure there are two such holes on each side adjacent and just inside of the transverse end strips 63 and also two holes on each side of the median strip 63. Since there are different matting strips for each pattern, there will be different locations for the holes 112 but such holes are always near the transverse strips.

Since the bubbles evolved during the electrolysis or sheet treating action are at the top 55 of the body of liquid within the chamber G some of the holes 112 will be near the top regardless of the position of the chamber at any particular time and such gas bubbles will be drawn off together with the liquid passing through the same 60 and also through the other holes 112. Such gas and liquid will be discharged into the troughs 111. A constant circulation of the electrolyte through the chamber G is thus maintained as 65 long as liquid enters the pipe 79 through the valve groove 95.

A series of drainage holes 113 are formed in the bottom wall of the trough 111 on the inside of each wheel B and the liquid electrolyte drains out from the trough when the particular frame element D is at the top as the wheel rotates.

The electrolyte which drains through the holes 113 falls onto the inclined surface of an annular flange 115 (Figs. 2, 5 and 6) which extends in from the inner side of the rim 56 of each wheel B. From this inclined surface the liquid is collected and returned to the sump 107 on that side of the machine.

A circular trough 116 of U-shape is located under the edge of each flange 115 and is held in place at the top by straps 117 which extend down from and are fastened to the frame beams 28. Each trough 116 is also secured by strap irons 118 (see also Fig. 1) to a gear casing 119 formed as an integral part of the bracket frame 43. There are two of these gear casings. As shown in Fig. 1, each trough member 116 is semi-circular and is under the upper half of its associated wheel B as the latter rotates.

Any liquid flowing over the edge of the flange 115 falls into the U-section of the trough 116 and then flows down on one side or the other of the vertical center line of the wheel. The liquid flowing to the right (Fig. 1) upon reaching the lower edge of the trough drops off into a semi-circular channel member 120 which extends just outside of and below each wheel B. This channel member is secured at 121 to the upright 25 at the top and rests on a strap 122 at the bottom. Strap 122 is in turn secured to one end of sump 107.

Channel 120 is also U-shaped in cross-section and at the bottom merges into a discharge chute 123 which opens out into and which is directly over the sump 107 on that side. It will be understood that there are two channels 120, one for each wheel B. The channel member 120 also extends above the discharge chute a slight distance to the left of the vertical center of the wheel B so that liquid falling into the channel member from the left also drops into the sump 107.

An intermediate drain 124 (Figs. 1 and 2) is provided at the side of each wheel B and extends up to a position just above the lower end of the left side of drain trough 116 (Fig. 1) to which it is fastened and where it catches the liquid draining from the trough. This intermediate drain at the bottom is secured to the channel member 120. Liquid received from the trough 116 is carried by the drain 124 to the inside edge of its wheel B and thereupon passes through a chute 125 which in turn empties into the channel member 120 at the bottom.

By carrying the drain liquid to the inside edge of each wheel the space between the two ends of the contacting part of each belt E on its wheel B is left free for feeding the sheets *a* into the wheels by the sheet feeding device A and for removing the sheets from the wheels by the discharge device F.

Since the pump 102 keeps the electrolyte circulating into the treating chambers G, liquid continues to flow out and back into the sump to be again drawn into the pump so long as there is a closed chamber G and so long as there is liquid in the chamber.

The two wheel holders B are rotated in unison by suitable connection with a unit drive shaft applied at the inside of the machine. A suitable connection is shown in Fig. 2 and ref-

erence should be had to this phase of the mechanism. Each drum 51 has the inner end of its hub 52 reduced where it extends inside of the gear casing 119 and a driven gear 126 is keyed on this reduced hub end of the drum.

At the bottom and extending across between the drums a shaft 127 is journaled in bearings 128 formed in depending bracket parts of the bracket frame 43. This shaft carries two pinions 129, each one keyed to the end of the shaft and each meshing with its gear 126. Shaft 127 also carries a bevel gear 131 which is driven by a gear 132 carried on a drive shaft 133. Shaft 133 is journaled in suitable bearings formed in an extension 134 which is an integral part of the bracket frame 43. In this manner the wheels B are rotated.

There is a belt E for each wheel holder B and the belts and the mountings will next be considered. Both endless belts are identical in size and mounting and are best shown in Figs. 1 and 11. When each belt is engaged on its wheel holder it is of course supported thereby and a number of pulleys are used to carry the belts in their proper paths when not in engagement.

Each belt in first coming into contact with its wheel B passes over a pulley 135. The two pulleys 135 of the two wheels B are mounted on a shaft 136 which is journaled in suitable bearings 30 131 formed in the sub-frame 33. Pulleys 135 are located below and forward of the rollers 34 and into such position as to properly receive a sheet *a* passing from roller 34. Idler rollers 138 may also be used at this position for both wheels 35 and the two idler rollers are mounted on a shaft 141 journaled in bearings 142 formed in the frame 33.

After the two belts E have passed in under, around and over the wheels B, each belt leaves 40 the wheel adjacent the sheet discharge device F. At this position it passes around a large pulley 146 and under an adjacent pulley 147. The two pulleys 146 are carried on a shaft 148 journaled in brackets 149 supported on the upright frames 45 25. The two pulleys 147 are carried on a shaft 151 which is journaled in brackets 152 supported on an auxiliary frame 153 secured to the uprights 25. Braces 154 are preferably used to further hold the frame 153.

Each belt upon leaving the pulley 147 next takes over a pulley 161 and the two pulleys 161 are mounted upon a shaft 162 which is journaled in brackets 163 depending from the upper frame beams 28. From pulley 161, the belt extends 55 across the wheel B and is spaced a slight distance above the other run of the belt on the wheel. It takes over a pulley 164 and the two pulleys 164 are mounted upon a shaft 165 which is journaled in brackets 166 also depending from the upper frame beams 28.

From the pulley 164 the belt passes over a pulley 167 and the two pulleys 167 are mounted upon a shaft 168 which is journaled in brackets 65 169 supported on the frame uprights 25. Each belt thence passes down to a point below its associated wheel B where it takes over a pulley 171. Pulleys 171 are mounted upon a shaft 172 which is journaled in brackets 173 resting upon the floor. From pulley 171 the belt passes horizontally below the wheel B and also under the sump 107 on its side of the machine, the two sumps being elevated above the floor.

It now passes under a pulley 174 and thence 70 75 back over pulley 135 at the point of commence-

ment. The two pulleys 174 are mounted on a shaft 175 journaled in the sub-frame 33.

It has already been stated that in the embodiment of the invention as disclosed in the drawings provision is made for automatically changing the direction of flow of the electric treating current in order to provide for anodic or cathodic treatment as desired. In other words, the polarity of the current effective on the electrolyte flowing into the chamber G is changed so that the sheet a may in the one case be made the anode and in the other case, the cathode. This shifting of the polarity of the current will now be considered.

The wires 66 and 72 of each treating chamber G constitute the two sides of the treating circuit as to that chamber. Each wire 66, as previously mentioned, is connected to its individual electrical brush 68 and in like manner each wire 72 is connected to a similar individual brush 73. Each brush 68 is adapted to engage and rotate over a commutator ring which is mounted on the cylindrical block 85 and in like manner each individual brush 73 is adapted to rotate over another commutator ring also mounted on the block adjacent to and inside of the other ring. The outermost commutator ring which is associated with the brushes 68 will be broadly referred to by the numeral 176 (see Fig. 8) and the inner ring for the brushes 73 will be broadly indicated by the numeral 177.

These commutator ring units 176, 177 are carried on the cylindrical block 85 and when different kinds of treatment are desired in the chambers G, the units are split, i. e., are made up in different sections. Provision is made in the present machine for changing the electrical polarity effective at the brushes 68, 73 when these brushes pass from one ring section to the adjacent ring section in its ring unit. As illustrated in Fig. 8, different ring sections are used to cause current to flow through the electrolyte in a precleaning step. In such cleaning there is first a short anodic treatment of the sheet a followed by a cathodic treatment to complete the cleaning operation. Following this the sheet is anodized. Part of each commutator ring also has a dead or blank section where no current is conducted to the commutator brushes, this being when a treated sheet is being removed from the wheel and a new sheet is being brought into place for treatment.

Both commutator ring units 176 and 177 are mounted on an insulating ring 178 which is carried in the cylindrical block 85. Ring 178 has two parallel peripheral grooves 179 and 180 (see Fig. 9) for the different sections which make up the respective commutator units 176, 177. In considering the various sections (four in number for the present treatment) of each commutator ring 176, 177, these will be taken in counterclockwise order as viewed in Fig. 8.

First as to the outer ring unit 176 and beginning with the blank or no-current section of that ring. Such a blank section comprises a curved strip 181 mounted in the groove 179. In the same groove, a second ring section 182 is spaced a slight distance from the end of the strip 181. Section 182 is the first of the current conducting sections and in the treatment of the sheet now being considered provides in part for an anodic cleaning step. In the same groove is a third curved commutator strip section 183 spaced from the end of section 182. This produces in part the cathodic cleaning step. Finally a fourth section 184 extends for a longitudinal distance equal

to substantially 180 degrees and one end of this latter strip is spaced from the end of strip 183 and its other end is spaced a slight distance from the blank strip section 181. The sheet anodizing treatment uses this section.

The inner commutator ring unit 177 also consists of four sections spaced from one another as to their end to end positions and all carried in the groove 180. The four sections correspond in length and relative positions to the sections of the commutator unit 176 so that the proper timing of the polarity changes in current for this side of the circuit will be effected.

The first of these ring sections of commutator unit 177 is a short strip 185 (Fig. 8) which is a blank section (no current) corresponding to blank section 181 of the other commutator. A second strip section 186 is mounted in the inner groove 180 and is spaced from the end of the section 185 and corresponds in length to the commutator strip 182 in the outer groove. It cooperates with the section 182 in producing the anodizing cleaning step. A third commutator strip section 187 is next in position in the groove 180 being spaced from the end of the strip 186. It cooperates with section 183 in the cathodizing cleaning step. The fourth commutator section is a relatively long strip 188 which corresponds in length and relative position to the commutator strip 184 and works with that side of the circuit in the sheet anodizing treatment.

At certain spaces or breaks between the ends of the several strip sections of each commutator unit, connecting wires 191 (indicated in Figs. 8 and 9 by broken lines) join a strip section in the outer groove with an adjoining strip section in advance in the inner groove. By reason of such cross-over electrical connections between the segments of the two commutator strip units 176, 177 adjacent sections in each unit carry different polarity. There are no wire connections to the two ends of the two blank sections 181, 185 but section 182 is joined with section 187 and section 186 is joined with section 183. Again section 184 joins section 187 and section 183 joins section 188.

The effect of this electrical wiring combination is to provide a positive current for an individual brush 68 during a portion of the rotation of the wheel B at which time the opposite or negative current is carried on the associated brush 73. At such a time sheet a is positive so that the treatment is then an anodic treatment. As soon as the wheel has carried those two particular brushes 68, 72 over the ends of the two adjacent strip sections the current flow is reversed and the sheet a being negative receives a cathodic treatment. Starting from the blank or no-current condition one complete revolution of the wheel B with the commutator sections described, the sheet a will be anodized and cathodized in a pre-cleaning step and will then be treated anodically. It will be understood that one or more steps may be eliminated or added as desired merely by changing the number of commutator sections.

The feed wires for bringing the treating current to the commutators are illustrated in Fig. 2 as wires 195, 196 which lead from any suitable source of electric current. These wires come into the machine at the center and are carried in a conduit pipe 197 which extends into the center of the hollow sleeve 41 and then branches in both directions passing to the ends of the sleeve where the wires 195, 196 on each wheel B are connected directly to the commutator strips 184,

188. By reason of the cross-over connection between sections current is also available in strips 187 and 182 from the connection with the strip 184 and in strips 183 and 186 from the strip 188.

Obviously, if only a single anodic treatment is desired the split sections of the two commutator strip units will be replaced by a single pair of unbroken strips. The length of the several strip sections determines the length of time the current flows for the treating operation and considerable leeway is therefore possible by merely changing the position and length of commutator strips. Obviously, the breaks that occur between the strips and which result in a change of polarity can be positioned in any desired place in the electrical block 85 and this permits of any desired timing for the treatment of the sheets.

After a sheet has been properly treated the inner end of a pipe 79 associated with its treating chamber G, passes beyond the groove 95 (Fig. 10) in the liquid valve which supplies the electrolyte and thereupon the flow of liquid into the chamber ceases. At the same time the liquid continues to drain out of the chamber and from the trough 111 associated with the frame element D in which the sheet is disposed. By the time the sheet has reached the discharge pulley 146 most of this liquid has drained out of the chamber G and any remaining liquid immediately flows into the trough 116 and thence, by way of the intermediate drains 124, back into the sump 107.

The sheet upon coming into the position where the belt E passes under and around the pulley 146 is stripped from its seat and passes around with the belt. To insure this correct passage of the sheet with the belt, the pulley 146 may be magnetized so that the magnetic flux operating through the belt peels the sheet off of the wheel B and passes it around with the belt under the pulley 146. The pulley 147 may also be magnetized and this will strip the sheet from the pulley 146.

To insure better delivery of the sheet as it passes through the discharge device an endless belt 198 is preferably provided to pass over the pulley 147 and also over a pulley 199. It will be understood that there are two pulleys 146, 147 and therefore there will be two belts 198 and two pulleys 199. The two pulleys 199 are mounted on a shaft 201 journaled in brackets 202 carried on the frame part 153. A sheet *a* passing onto the belt 198 is discharged in this manner into a suitable place of deposit.

After a sheet *a* has been treated according to the various steps just described, that part of its surface (marked X in Fig. 12) which was blocked off by the matting strips 63 will be in its same original condition as before treatment. That part of the surface (marked Y) which was exposed to the electrolyte in the different treatments is changed and is now an anodized surface capable of resisting certain chemical changes by contact with the can contents as fully described.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an apparatus for electrically treating

the surface of sheet material, the combination of a rotatable wheel holder having a series of pockets formed at intervals in its peripheral face, means for rotating said holder, a clamping belt adapted for operation over a major part of the wheel's periphery for holding a sheet on said holder and within a said pocket so that it is electrically connected in an electrical treating circuit with the surface areas of the sheets which are to be treated exposed to the interior of its said pocket, pulleys rotatably mounted adjacent said wheel holder for guiding and supporting said belt where it leaves and where it engages the periphery of the wheel, a minor part of the wheel holder periphery thus being left unengaged, feeding devices located adjacent the exposed peripheral part of said wheel holder for positioning a sheet to be treated within a pocket of the holder prior to the sheet being clamped by said belt, means for bringing an electrolyte into said pocket and into contact with the exposed area of said held sheet, and means for passing an electric treating current through said electrolyte and through the sheet so as to treat said exposed sheet area during the rotation of said holder and prior to the sheet reaching the leaving position of the belt relative to the holder.

2. In an apparatus for electrically treating the surface of sheet material, the combination of a wheel holder having a series of pockets formed at intervals in its peripheral face, a clamping belt adapted for operation over a major part of the wheel's periphery for holding a sheet on said holder and within a said pocket, pulleys rotatably mounted adjacent said wheel holder for guiding and supporting the belt where it leaves and where it engages the periphery of the wheel, a minor part of the wheel holder periphery being free of the belt, feeding devices located adjacent the exposed peripheral part of said wheel holder for positioning a sheet to be treated within a pocket of the holder so that it is easily clamped by said belt, discharge devices also located adjacent the exposed peripheral part of the holder for removing the treated sheet from the holder when the belt has left its periphery, means for bringing an electrolyte into said pocket and into contact with the exposed area of said held sheet while the pocket is closed by the sheet, means for passing an electric treating current through said electrolyte and through the sheet so as to treat said exposed sheet area during the passage of the sheet while held by the belt in said holder pocket, and means for controlling the actuation of said current means so that the treating circuit operates only so long as electrolyte is in said pocket.

3. In an apparatus for cathodizing and anodizing the surface of sheet material, the combination of a rotatable wheel holder for the sheet to be treated, said holder having a plurality of peripheral chambers for receiving a liquid electrolyte, each of said chambers having a radially disposed conduit for conducting the electrolyte to said chamber, means for clamping the sheet on the periphery of said holder within a said chamber as a part of an electrical treating circuit including said holder and exposing predetermined surface areas only of the sheet which are to be treated, means for radially projecting said electrolyte under pressure through said conduits into said chambers into contact with said exposed sheet areas, and means for passing an electric treating current through said electrolyte,

first in one direction and then in the other to both cathodize and anodize the treated areas of the sheet.

4. In an apparatus for cathodizing and anodizing the surface of sheet material, the combination of a rotatable wheel holder for the sheet to be treated, said holder having a plurality of peripheral chambers for receiving a liquid electrolyte, each of said chambers having a radially disposed conduit for conducting the electrolyte to said chamber, means for rotating said holder, means for clamping the sheet on the periphery of said holder within a said chamber as a part of an electrical treating circuit including said holder and exposing predetermined surface areas only of the sheet which are to be treated, means for radially projecting said electrolyte under pressure through said conduits into said chambers into contact with said exposed sheet areas, means for passing an electric treating current through said electrolyte and said sheet, first in one direction and then in the other to both cathodize and anodize the treated areas of the sheet, and means controlled by the rotation of said holder for shutting off the flow of electric current to a sheet in a chamber having no electrolyte therein.

5. In an apparatus for precleaning and then anodically oxidizing the surface of sheet material, the combination of a rotatable wheel holder for the sheet to be treated, said holder having a plurality of spaced peripheral chambers for receiving a liquid electrolyte and a plurality of radially disposed conduits for conducting the electrolyte to said chambers respectively, means for rotating said holder, means for clamping separate sheets on the periphery of said holder respectively within said chambers so that each sheet constitutes a part of an electrical treating circuit including said holder and exposing predetermined surface areas only of the sheets which are to be treated, means controlled by the rotation of said holder for radially projecting said electrolyte under pressure through said conduits into said chambers into contact with said exposed sheet areas, means for passing an electric treating current through said electrolyte, first with a said sheet as an anode and then as a cathode to preclean the exposed surface areas of the sheet, and means for again converting said current to thereafter anodically treat the sheet with the sheet as an anode in said circuit and while said electrolyte is maintained in contact therewith so as to anodically oxidize the treated sheet areas.

6. In an apparatus for precleaning and then anodically oxidizing the surface of sheet material, the combination of a rotatable wheel holder for the sheet to be treated, said holder having a plurality of spaced peripheral chambers for receiving a liquid electrolyte and a plurality of radially disposed conduits for conducting the electrolyte to said chambers respectively, means for rotating said holder, means for clamping separate sheets on the periphery of said holder respectively within said chambers so that each sheet constitutes a part of an electrical treating circuit including said holder and exposing predetermined surface areas only of the sheets which are to be treated, means controlled by the rotation of said holder for radially projecting said electrolyte at predetermined intervals under pressure through said conduits into said chambers into contact with said exposed sheet areas, means for passing

an electric treating current through said electrolyte, first with a said sheet as an anode and then as a cathode to preclean the exposed surface areas of the sheet, means for again converting said current to thereafter anodically treat the sheet with the sheet as an anode in said circuit and while said electrolyte is maintained in contact therewith so as to anodically oxidize the treated sheet areas, and means operating

5 in time with the rotation of said holder for shutting off the flow of electrolyte to said chambers when the sheets are being placed on and removed from said holder.

7. In an apparatus for treating sheet material, 15 the combination of a rotatable wheel holder having a plurality of spaced pockets formed in its periphery, each of said pockets constituting a sheet treating chamber for holding a liquid electrolyte in contact with a predetermined surface 20 area of said sheet, means for rotating said holder, a matting device carried in each of said chambers and arranged to expose a predetermined surface area of a said sheet in a definite pattern, while covering the remaining surface 25 area of the sheet, sheet feeding devices for placing a sheet to be treated on the periphery of the wheel in position on a said matting device so that its pattern is outlined on the inner surface of the sheet, an endless clamp belt engaging and 30 operating over the periphery of said wheel holder for pressing against the outer surface of a said sheet to retain the sheet on the holder within a said chamber, means controlled by the rotation of said holder for introducing an electrolyte 35 into a said chamber in contact with the parts of the inner surface of the sheet disposed inside of its pattern outline and exposed by said matting devices, and means for passing an electric current through said electrolyte and also through 40 said sheet to electrically change the surface condition of the sheet.

8. In an apparatus for treating sheet material, 45 the combination of a rotatable wheel holder having a plurality of spaced pockets formed in its periphery, each of said pockets constituting a sheet treating chamber for holding a liquid electrolyte in contact with a predetermined surface area of said sheet, means for rotating said holder, a matting device carried in each of said chambers and arranged to expose a predetermined surface area of a said sheet in a definite pattern while covering the remaining surface area of the sheet, sheet feeding devices for placing a sheet to be treated on the periphery of the wheel

50 in position on a said matting device so that its pattern is outlined on the inner surface of the sheet, an endless clamp belt engaging and operating over the periphery of said wheel holder for pressing against the outer surface of a said sheet to retain the sheet on the holder within a said chamber, means controlled by the rotation of said holder and timed therewith for introducing an electrolyte at predetermined intervals

55 into a said chamber in contact with the parts of the inner surface of the sheet disposed inside of its pattern outline and exposed by said matting devices, means for passing an electric current through said electrolyte and also through said sheet to electrically change the surface condition of the sheet, and means controlled by the rotation of said holder for shutting off the flow of electric current to a chamber having no electrolyte therein.

60 70 75 9. In an apparatus for electrically treating metallic sheet material, the combination of a

double wheel sheet holder for holding sheets for treatment, devices for rotating said wheels on a common axis, each of said wheels having a plurality of recesses formed in its peripheral surface to constitute individual sheet treating chambers, resilient matting devices located in said chambers for outlining the area of the sheet to be treated when a sheet is disposed in a said chamber, means including a pair of belts, one for each wheel for clamping a sheet on a said resilient matting device so as to cover over its chamber within the outlines of said matting device, the portions of the inner surface of the clamped sheet not engaging said matting devices being exposed to the interior of said chamber, means for radially introducing and circulating a liquid electrolyte from the axis of said wheels into each of said chambers when a said chamber is closed by a sheet so that the liquid contacts the exposed surface of the sheet, and means for passing an electric current through said electrolyte and through a said sheet to surface treat the sheet.

10. In an apparatus for electrically treating metallic sheet material, the combination of a double wheel sheet holder for holding sheets for treatment, devices for rotating said wheels on a common axis, each of said wheels having a plurality of recesses formed in its peripheral surface to constitute individual sheet treating chambers, resilient matting devices located in said chambers for outlining the area of the sheet to be treated when a sheet is disposed in a said chamber, means including a pair of belts, one for each wheel for clamping a sheet on a said resilient matting device so as to cover over its chamber within the outlines of said matting device, the portions of the inner surface of the clamped sheet not engaging said matting devices being

- exposed to the interior of said chamber, a source of liquid electrolyte, means for radially introducing and circulating said liquid electrolyte from said source through the axis of said wheels into each of said chambers when a said chamber is closed by a sheet so that the liquid contacts the exposed surface of the sheet, means for preventing access of the liquid to said chambers when the sheets are being placed on the periphery of said wheel and removed therefrom, means for passing an electric current through said electrolyte and through a said sheet to surface treat the sheet, and means for returning the liquid electrolyte from said chambers to said source to be recirculated therefrom.
11. In an apparatus for electrically treating metallic sheet material, the combination of a wheel sheet holder for holding sheets for treatment, means for rotating said wheel, said wheel having a plurality of recesses formed in its peripheral surface to constitute individual sheet treating chambers, resilient matting devices located in said chambers for outlining the area of the sheet to be treated when a sheet is disposed in a said chamber, means including a belt for clamping a sheet on a said resilient matting device so as to cover over its chamber within the outlines of said matting device, the portions of the inner surface of the clamped sheet not engaging said matting devices being exposed to the interior of said chamber, means for radially introducing and circulating a liquid electrolyte from the axis of said wheel into each of said chambers when a said chamber is closed by a sheet so that the liquid contacts the exposed surface of the sheet, and means for passing an electric current through said electrolyte and through a said sheet to surface treat the sheet.

HORACE J. PAYNTER.
